DESIGN FOR A LANTERN SLIDE TRAY

Henry J. Hood, Rochester, N. Y., assignor to Eastman Kodak Company, Rochester, N. Y., a corporation of New Jersey

Application September 29, 1939, Serial No. 87,439

Term of patent 14 years

To all whom it may concern:

Be it known that I, Henry J. Hood, a citizen of the United States of America, residing at Rochester, in the county of Monroe and State of New York, have invented a new, original, and ornamental Design for a Lantern Slide Tray, of which the following is a specification, reference being had to the accompanying drawing, forming a part thereof.

In the drawing:

Fig. 1 is a perspective view of a lantern slide tray showing my new design.

Fig. 2 is a side elevation of the lantern slide tray shown in Fig. 1.

Fig. 3 is a top plan view of the lantern slide tray shown in the preceding figures.

Fig. 4 is an end elevation of the lantern slide tray showing the left-hand end of the tray shown in perspective in Fig. 1, and

Fig. 5 is an end elevation showing the opposite end of the lantern slide tray.

I claim:

The ornamental design for a lantern slide tray, as shown.

HENRY J. HOOD.
